UNITED STATES PATENT OFFICE.

LOUIS SOLVAY, OF BRUSSELS, BELGIUM.

SEPARATION OF TAR AND AMMONIUM CHLORID CONTAINED IN GASES PRODUCED BY DISTILLING COAL.

1,052,853.

Specification of Letters Patent. Patented Feb. 11, 1913.

No Drawing.

Application filed March 18, 1912. Serial No. 684,356.

To all whom it may concern:

Be it known that I, Louis Solvay, a subject of the King of the Belgians, residing at Brussels, Belgium, have invented 5 new and useful Improvements in Separation of Tar and Ammonium Chlorid Contained in Gases Produced by Distilling Coal, of which the following is a specification.

10 This invention relates to improved separation of tar and ammonium chlorid contained in gases produced by distilling coal in coke ovens and gas works.

By the use of apparatus such as described 15 in the specification of prior Letters Patent No. 963,401 in which the gases produced by distilling coal are washed in a bubbling column or gas scrubber with tar, the tar contained in the gases can be easily removed 20 and the saturation of the ammonia, that is to say the combination of the ammonia with acid to form a salt can then be easily effected by direct washing of the gases in sulfuric acid after the tar is removed. The

25 apparatus described in the said prior specification enables different temperatures to be obtained in the different superposed sections or compartments of the bubbling column or scrubber, and, by suitably regulating the

30 temperatures, a practically anhydrous tar can be withdrawn directly from the treated gases, the commercial value of such tar being greater than that of tar which contains water. Such a method of working has how-

35 ever a disadvantage in that the separation of ammonia already in combination in the gases as ammonium chlorid and which condenses with the tar in a quantity which is variable, and, in the case of certain coals, 40 often considerable, is a delicate operation requiring special manipulation and only giving imperfect results.

The object of the present invention is to 45 obviate this disadvantage. According therefore to the ammonium chlorid is separated in a solid state from the gas previous to the introduction of the latter into the apparatus for removing the tar.

50 Since the apparatus directly receives the tar which is already condensed in the hydraulic main of the furnaces all separation or sublimation, hereinafter termed condensation of the ammonium chlorid therein should be avoided and this may be effected by preventing the local causes of cooling. On the

other hand notwithstanding the large gaseous volumes to be treated and the well known considerable vapor tension of ammonium chlorid, it is necessary to prevent any of the ammonium chlorid being carried along 60 by the gases. Now it has been ascertained that if the gases issuing from the hydraulic main are cooled on their way to the tar removing apparatus to a temperature which may vary from 180 to 120 (one hundred and 65 eighty to one hundred and twenty) degrees centigrade, according to the amount of chlorid contained in the gases, a small portion of the tar will be deposited and, owing probably to its vesicular state, carry with it the 70 particles of ammonium chlorid which it retains completely. From this it will be understood that it is sufficient to avoid all condensation of the ammonium chlorid in the hydraulic main in order to be able to effect 75 the total condensation thereof into a solid state in a cooling apparatus of any suitable kind placed between the hydraulic main and the apparatus for removing the tar. In order to facilitate the removal of the condensed salt by washing or otherwise two coolers may be used so arranged that the 80 salt may be removed from one while the other is working.

The general working of the process may 85 therefore be as follows: The gases pass through the hydraulic main which is maintained as hot as possible by a suitable jacket to prevent any condensation of the ammonium chlorid. A temperature of about 90 350° C. is sufficient for this purpose. The gases then pass into a cooler where their temperature is lowered to from 180 to 120 (one hundred and eighty to one hundred and twenty) degrees centigrade so that the 95 ammonium chlorid which they contain is deposited therein. The gases are then led to the tar removing apparatus from whence they pass to the sulfuric acid saturator.

It will be seen that the improved process 100 permits of the direct recovery of the ammonium chlorid in the solid state independently of the recovery of an anhydrous tar of a quality superior to that of ordinary tar.

Having now described my invention, what 105 I claim as new and desire to secure by Letters Patent is:—

1. Process for the separation of tar and ammonium chlorid contained in the gases produced by distilling coal, consisting in 110

2
maintaining the said gases at a sufficient temperature in the hydraulic main of the furnaces to prevent condensation therein of ammonium chlorid, then after the said gases have left the hydraulic main their temperature is lowered sufficiently to cause the ammonium chlorid to deposit simultaneously with a small portion of the tar and the said gases are finally passed through a suitable tar removing apparatus wherein condensation of water vapor is avoided by maintaining therein suitable temperatures.

2. Process for the separation of tar and ammonium chlorid contained in the gases produced by distilling coal consisting in maintaining a sufficient temperature in the hydraulic main of the furnace to prevent condensation therein of ammonium chlorid, causing the gases issuing from said main to pass through a suitable cooling apparatus wherein they are cooled to a temperature of 180 to 120 degrees centigrade and afterward through a tar removing apparatus wherein the temperature is maintained such as to avoid condensation of water vapor therein.

3. Process for the separation of tar and

ammonium chlorid contained in the gases produced by distilling coal consisting in first separating the ammonium chlorid together with a small portion of the tar by cooling the gases issuing from the hydraulic main to a temperature of 180-120° C. and afterward separating the remaining portion of the tar in a practically anhydrous condition.

4. In the separation of practically anhydrous tar from the gases produced by distilling coal, the process for obtaining nearly all the tar free from ammonium chlorid consisting in maintaining a temperature of about 350° C. in the hydraulic main, lowering to 180-120° C. the temperature of the gases between said hydraulic main and the tar remover and maintaining a suitable temperature in the latter to avoid condensation of water vapor therein.

In testimony whereof I have affixed my signature in presence of two subscribing witnesses.

LOUIS SOLVAY.
